UNITED STATES PATENT OFFICE.

RICHARD C. RATTO, OF COLDWATER, MICHIGAN, ASSIGNOR TO CHAMPION BRASS WORKS, OF COLDWATER, MICHIGAN, A CORPORATION OF MICHIGAN.

DESIGN FOR AN ARM FOR LIGHTING-FIXTURES.

57,443.

Specification for Design.

Patented Mar. 29, 1921.

Application filed September 2, 1920. Serial No. 407,812. Term of patent 3½ years.

To all whom it may concern:

Be it known that I, RICHARD C. RATTO, a citizen of the United States, residing at Coldwater, in the county of Branch and State of Michigan, have invented a new, original, and ornamental Design for an Arm for Lighting-Fixtures, of which the following is a specification, reference being had to the accompanying drawing, forming part thereof.

Figure 1 is a side elevation of an arm for lighting fixtures, showing my new design.

Fig. 2 is a top view of the same.

I claim:

The ornamental design for an arm for lighting fixtures as shown.

RICHARD C. RATTO.
